UNITED STATES PATENT OFFICE

CLIFTON B. DAVIDSON, OF DECATUR, ILLINOIS

SWITCH STAND

Application filed March 28, 1932. Serial No. 601,611.

This invention relates to a switch stand and particularly to an improved means for preventing accidental disengagement of the locking means and thereby avoiding accidents which might result therefrom.

Prior to my invention these devices have been dangerous either because of failure to provide any means for preventing accidental disengagement of the locking means or because the means provided was not sufficiently simple or easily operated to avoid the temptation to operatives to neglect the proper precautions.

Accordingly it is an object of my invention to provide a safety latch which shall be simple and extremely easily operated whereby to safeguard against accidents to the very largest possible extent.

I attain the foregoing and other and more limited objects in and through the construction and arrangement of parts hereinafter described and claimed and illustrated in the accompanying drawing in which Fig. 1 is a fragmentary vertical sectional view showing a switch stand of substantially the usual construction with the addition of my improved safety device and Fig. 2 is a plan view of the structure shown in Fig. 1.

Referring now to the drawing, the numeral 10 indicates a plate or table, which is preferably supported by uprights or legs of usual construction (not shown), and which will be provided with notches 11. Extending through the table or plate 10 is an upright shaft 12 which is adapted to be connected in operating relation to the switch whereby to operate the same when it is rotated. The shaft 12 also passes through a movable member 13 and is secured against rotation with respect thereto as by a pin 14. The movable member 13 preferably is movable over the table 10 in substantial contact therewith as indicated although it may be spaced therefrom if desired. The member 13 is provided with a slotted projection extending laterally from the main body thereof. The projection is generally indicated by the numeral 15 and the slot therein by the numeral 16. Pivoted within the slot 16 as by a pin 18 is a locking lever 17. This lever projects a considerable

distance below the pivot point and terminates in a handle, not shown. This lever also extends above the pivot 18 and above the inner portion of the projection 15. A web 19 may connect the two portions of the projection 15 at the sides of the slot 16 and may be carried by an upward extension whereby to form a stop for the upper end of the locking lever 17. The foregoing construction is common practice and per se forms no part of my invention.

Clamped to the shaft 12 are a pair of clamp members 20 and 21 urged into clamping relation with the shaft 12 by suitable bolts 22 and 23. Extending between the downturned end portions of the members 20 and 21 is a sleeve 24 which is caused to be tightly gripped between such end portions by a bolt 25 extending therethrough. Pivoted on the sleeve 24 is a stout locking bar 26. Extending transversely of the bar 26 at the end thereof and welded to the lower surface is a positioning bar 27. Connected by welding or any equivalent manner to the bar 26 intermediate the ends thereof is a T-shaped handle member 28 which extends upwardly and the arms of which extend laterally beyond the movable member 13 as is clearly indicated in Fig. 2.

From the foregoing it is obvious that when the latch, comprised of the members 26, 27 and 28, is in the position shown in Fig. 1, the locking lever 17 cannot be rotated counterclockwise and therefore cannot become disengaged from the notches 11. When the latch is in "up" position, that is, moved out of the path of the upper end of the lever 17, the switch can be operated in the usual manner. It is within contemplation of my invention to provide shoulders 29 on the members 20 and 21 which shall act as stops to limit the upward motion of the bar 26. These may be positioned so as to prevent the center of gravity of the latch moving to the left of the pivot 25 if it is desired that the same shall always return automatically under the action of gravity to latching position. This, while eliminating the necessity for attention on the part of the operative, is somewhat less convenient since he must hold it in "up" position while he rotates the lever 17 out of the 100

notch 11. If this should be undesirable it would be possible to make the handle 28 of such upward extent and of such weight that the center of gravity would be at the left of the pivot 25; or the shoulders 29 might be positioned to secure this effect. It is, however, preferred that the latch shall automatically return to the position shown in Fig. 1 when the lever 17 is moved to locking position.

While I have shown and described the preferred embodiment of my invention I wish it understood that I am not limited to the details illustrated, since, obviously, changes may be made without departure from the spirit and scope of the appended claims.

Having thus described my invention, what I claim is:

1. In combination with a switch stand having the usual fixed table provided with notches, an upright shaft passing therethrough and adapted to be connected in operating relation to a switch, a movable member carried by said shaft and movable over said table for operating the shaft, an operating lever pivoted thereto and adapted to be received in said notches, a clamp connected to said shaft and a latch pivoted to said clamp and adapted to fall in behind the upper end of said lever to prevent accidental removal of the same from said notches.
2. In combination with a switch stand having a table provided with a plurality of notches, an upright shaft adapted to control a switch, a movable member carried by said shaft and projecting laterally therefrom and provided with a pivoted locking lever adapted to engage in said notches and extending beyond a portion of said movable member, of a clamp connected to said shaft and carrying a latch member pivotally connected thereto and adapted to engage behind a portion of said lever for preventing accidental disengagement thereof from said notches.

3. As a sub-combination for use in connection with a railway switch, a clamp member consisting of opposed portions and means for drawing them together and a latch member pivoted therebetween and comprising a bar having a transverse positioning member connected at the end thereof and a handle member connected thereto intermediate the ends and extending upwardly and laterally for convenient gripping.

4. In a device of the character described, a table member provided with a plurality of notches, a vertical shaft adapted to control a switch, a movable member carried by said shaft extending laterally therefrom and movable over said table for rotating the shaft, a lever pivotally connected to said movable member adapted to enter one of said notches and having a portion extending above said movable member, a latch pivoted with respect to said movable member and comprising a stout bar adapted to be moved

behind the upwardly extending portion of said lever, a transverse member connected thereto and adapted to engage said movable member for positioning said bar and a T-shaped handle connected to said bar intermediate the ends thereof and having the arms of the T projecting laterally beyond the edges of said movable member for convenient grasping.

5. As a sub-combination for use in connection with a railway switch, a clamp means and a latch member pivoted thereto and comprising a bar having a transverse positioning member connected at the end thereof and a handle member connected thereto intermediate the ends and extending upwardly and laterally for convenient grasping.

6. In a device of the character described, a table member provided with a plurality of notches, a vertical shaft extending therethrough and adapted to control a railway switch, a movable member carried by said shaft for rotating the same extending laterally therefrom and movable over said table, a lever pivotally connected to said movable member adapted to enter said notches and having a portion extending above said movable member, a clamp connected to said shaft above said movable member, a latch pivoted to said clamp and comprising a bar adapted to be moved behind the upwardly extending portion of said lever, a transverse member connected thereto and adapted to engage said movable member for positioning said bar and a T-shaped handle connected to said bar intermediate the ends thereof and having the arms of the T projecting laterally beyond the edges of said movable member for convenient grasping.

In testimony whereof, I hereunto affix my signature.

C. B. DAVIDSON.
